UNITED STATES PATENT OFFICE.

JAMES POWERS, OF NEW YORK, N. Y., ASSIGNOR, BY MESNE ASSIGNMENTS, TO POWERS ACCOUNTING MACHINE COMPANY, OF NEW YORK, N. Y., A CORPORATION OF DELAWARE.

SINGLE HAND PERFORATING-MACHINE.

1,086,853.

Specification of Letters Patent.

Patented Feb. 10, 1914.

Application filed September 9, 1912. Serial No. 719,262.

To all whom it may concern:

Be it known that I, JAMES POWERS, a citizen of the United States, residing in New York city, in the county of New York and State of New York, have invented certain new and useful Improvements in Single Hand Perforating-Machines, of which the following is a specification.

This invention has for its object to provide an improved form of apparatus for punching holes throughout the greater portion of the face of a card or similar object, whereby an operating member, such as a plunger to be engaged by the hand, is readily shiftable longitudinally and transversely over the face of the card to be brought to a large number of positions, and thereupon the plunger is struck or depressed by the hand to effect the punching of a hole in the card.

A further object is to provide a form of carriage movable in one direction across the face of a card that is suitably supported, and also a form of carrier movable in another direction on the carriage.

In the accompanying drawing, showing one embodiment of my invention, Figure 1 is an end elevation of the device; Fig. 2 is a plan view with the intermediate portion broken away; Fig. 3 is a longitudinal section on the line 3—3 of Fig. 2; Fig. 4 is a cross section on the line 4—4 of Fig. 2; Fig. 5 is a vertical section, enlarged, through the plunger and the adjacent portion of the punches; Fig. 6 is a similar view with the plunger and one of the punches advanced to perforate the card; Fig. 7 is a plan view with the carriage and plunger in different positions from that shown in Fig. 2; and, Fig. 8 shows a perforated card.

The device is shown as comprising a base or frame 12, formed of side members 13 and 14 connected by cross members 15 and 16. The side members 13 and 14 constitute guideways which support the ends of a carriage 17, whose end portions 18 and 19 slide on the guideways, preferably by suitable bearing members, such as a set of balls 20 and 21 on the two sides respectively, that operate in grooves 22 and 23 in the guideways, and grooves 24 and 25 in the carriage portions; stop-plates 26 being provided on each side of the carriage ends to prevent displacement of the ball series as the carriage is advanced.

It will be observed from the plan views, Figs. 2 and 8, that the carriage extends transversely across the base and is slideable longitudinally of the base. The carriage 17 is provided with a plurality of socket portions extending in a series along the carriage, a set of seven sockets 27 are shown, in each of which is mounted a punch 67 provided with a head 28 at the upper enlarged portion of the socket. A coil spring 65 29 is arranged in the enlarged portion between the head and the bottom wall of the enlargement, for the purpose of elevating the punch when depressed. If desired the lower cutting end of the punch may be made 70 concave to provide a cutting edge at the periphery. In their normal position, the punches do not extend below the bottom of the body 30 of the carriage, but when the punches are depressed by suitable means 75 they will project through the socket for perforating the card.

A suitable die-plate is provided that is preferably made a part of the carriage member, and a plate 31 is secured to the lower 80 face of the carriage member 30 and provided with a series of holes 32 registering with the punches 67; this plate 31 being offset a short distance from the plate or carriage 30 to admit the insertion of the card 85 between the punches and the die-plate, so that when the punch is brought down it will enter the aperture in the die after passing through the card to cut the desired opening 90 therein. As soon as released, the punch will be elevated by its spring and be thus raised out of the die-plate and above the space between the punch-plate and the die-plate.

Since the carriage travels longitudinally on the base, and would tend to move the card 33 placed in the space between the punch-plate and the die-plate, along with it, it is desirable to provide a stationary means for supporting the card, and a pair of bars 34 and 35 are provided, secured at 95 their extremities in the cross members 15 and 16 to the base, as shown in Fig. 8. These bars slide in socket portions 36 and 37, respectively, in the carriage located at the two ends of the open space between the punch-plate and the die-plate; and the bars are provided with slots or sockets 39 and 40, respectively on their opposing faces that receive the longitudinal edges of the card, as best shown in Fig. 5.

Instead of providing a separate actuating means for each of the punches, I provide a plunger member that is shiftable across the carriage to be brought to position to engage any one of the several punches shown. A carrier is shown in the form of a block 41 that is slidable between the longitudinal ribs or extensions 42 and 43 at the top of the carriage, being retained in position by over-hanging strips 44 and 45. This block has an aperture 46 in which slides the stem 47 of the plunger member which may be provided with a head 48 for convenience in operating. A spring 49 surrounds the stem 47 between the head and the block, and serves to elevate the plunger when depressed; a stop-pin 50 on the lower end of the stem engaging the block to limit the upward movement of the plunger by the spring. It will be readily understood that this block can be shifted along the carriage so that the plunger can be brought to register with any one of the seven punches, and when in such position the plunger is moved downwardly or given a blow that will cause it to engage the head of the registering punch and advance the latter to pass through the card into the die-plate. When released, the spring will withdraw the plunger to its former position and the spring on the punch operated will move the latter upward out of the card.

For convenience in moving the carriage a certain predetermined unit distance as desired between the apertures to be punched, a pointer 52 is provided on the carriage that registers with a set of numbers 53 on the side member of the carriage. To insure accuracy, a spring-arm 54 is provided on the carriage that engages a pin 55 carried in a bore in the carriage, that is pressed by the spring into a series of shallow sockets 56 in the frame, that correspond in position to the set of numbers 53. Similar means are provided for accurately positioning the carrier in its movement across the carriage, a pointer 57 being provided on the carrier that will move across a series of numbers 58 on the carriage. And a spring-arm 59 on the carrier enters a series of shallow sockets 60 on the carriage corresponding with the set of numbers.

In the use of the device, the card is inserted in the sockets in the two supporting bars, and the plunger head is grasped by the hand, that will serve to shift the carriage longitudinally along the base to any desired position, and thereupon the plunger can be shifted by sliding it along the carriage to register with any desired number, the said spring devices serving to accurately position both the carriage and the carrier. Thereupon it is only necessary to force the plunger down when the card will be perforated at that place, which is a very quick

operation and easily performed. Either the carriage or plunger, or both, are then shifted to a new position and thereby a large number of perforations can be produced in the card, such as indicated in Fig. 8.

To properly position the card 33 in the guide-bars 34 and 35, a stop plate 68 is arranged projecting up from the end plate 15 against which the end of the card is brought upon being inserted at the other end of the machine. When the card has been brought to this position it is secured by means of a pin 69 placed in holes 70 in the bar 35.

Having thus described my invention, I claim:

1. In a manual card punching device, a base having a pair of guideways, a carriage slidable in the guideways, the carriage having a series of sockets extending across it transversely to its path of movement, a punch located in each of the sockets, a carrier on the carriage, a plunger movable on the carrier, the carrier being shiftable across the carriage to bring the plunger to register with the said punches successively, and a die plate offset a short distance from the socket portions and provided with holes for registering with the said punches.

2. In a manual card punching device, a base having a pair of guideways, a carriage slidable in the guideways, the carriage having a series of sockets extending across it transversely to its path of movement, a punch located in each of the sockets, a carrier on the carriage, a plunger movable on the carrier, the carrier being shiftable across the carriage to bring the plunger to register with the said punches successively, and a die plate on the carriage offset a short distance from the socket portions and provided with holes for registering with the said punches.

3. In a manual card punching device, a base having a pair of guideways, a carriage slidable in the guideways, the carriage having a series of sockets extending across it transversely to its path of movement, a punch located in each of the sockets, a carrier on the carriage, a plunger movable on the carrier, the carrier being shiftable across the carriage to bring the plunger to register with the said punches successively, a die plate offset a short distance from the socket portions and provided with holes for registering with the said punches, and fixed means carried by the base for supporting a card to be perforated by the punches when actuated by the plunger.

4. In a manual card punching device, a base having a pair of guideways, a carriage slidable in the guideways, the carriage having a series of sockets extending across it transversely to its path of movement, a punch located in each of the sockets, a carrier on the carriage, a plunger movable on

- the carrier, the carrier being slidable across the carriage to bring the plunger to register with the said punches successively, a die plate on the carriage offset a short distance 5 from the socket portions and provided with holes for registering with the said punches, and fixed means carried by the base for supporting a card to be perforated by the punches when actuated by the plunger.
- 10 5. In a manual card punching device, a base having a pair of guideways, a carriage slidable in the guideways, the carriage having a series of sockets extending across it transversely to its path of movement, a punch located in each of the sockets, a carrier on the carriage, a plunger movable on the carrier, the carrier being slidable across the carriage to bring the plunger to register with the said punches successively, a die plate on the carriage offset a short distance 35 from the socket portions and provided with holes registering with the said punches respectively, and a pair of bars supported at their ends on the base and located at each side of the carriage and provided with sockets on their opposing faces to receive the edges of the card and support it between the die plate and the punches in the different positions of the carriage on the base.
- 15 6. In a manual card punching device, a base having a pair of guideways, a carriage slidable in the guideways, the carriage having a series of sockets extending across it transversely to its path of movement, a punch located in each of the sockets, a carrier on the carriage, a plunger movable on the carrier, the carrier being slidable across the carriage to bring the plunger to register with the said punches successively, a die plate on the carriage offset a short distance 40 from the socket portions and provided with holes registering with the said punches respectively, and a pair of bars supported at their ends on the base and located at each side of the carriage and provided with sockets on their opposing faces to receive the edges of the card and support it between the die plate and the punches in the different positions of the carriage on the base.
